UNITED STATES PATENT OFFICE.

GEORGE E. ABBOTT, OF WEST HARTFORD, CONNECTICUT, ASSIGNOR TO THE ABBOTT BALL COMPANY, OF WEST HARTFORD, CONNECTICUT, A CORPORATION OF CONNECTICUT.

BALL-BLANK-FORMING MACHINE.

Application filed April 15, 1924. Serial No. 706,877.

My invention relates to the class of machines employed to form blanks to be shaped into balls for burnishing purposes, for bearings and for other purposes, and an object 5 of my invention, among others, is the production of a machine of this class that shall be rapid in production and particularly efficient in operation.

One form of a machine embodying my invention and in the construction and use of which the objects herein set out, as well as others, may be attained, is illustrated in the accompanying drawings, in which—

Figure 1 is a view in side elevation of my 15 improved ball-blank forming machine.

Figure 2 is a view, substantially the not wholly, in vertical section of a plane passing lengthwise through the axis of the spindle of the machine and as denoted by the dotted 20 line 2—2 of Figure 6.

Figure 3 is a detail view in central vertical section of a portion of the structure on a plane denoted by the dotted line 3—3 of Figure 6.

Figure 4 is a view in section of a portion 25 of the structure on a plane denoted by the dotted line 4—4 of Figure 5, parts underneath being omitted.

Figure 5 is a view in section substantially 30 on a plane denoted by the dotted line 5—5 of Figure 2, parts beyond being omitted.

Figure 6 is a view in section on a plane denoted by the dotted line 6—6 of Figure 2, with parts beyond omitted.

Figure 7 is a view on a plane denoted by 35 the dotted line 7—7 of Figure 2, but with the pulley only removed.

Figure 8 is a perspective view of a fragment of the ball-blank cutting mechanism.

Figure 9 (sheet 1) is a view, scale enlarged, of a portion of the ball-blank cutter of a modified form.

Figure 10 (sheet 1) is a view, scale enlarged, of a ball blank produced by the operation of my improved machine and with the cutter shown in Figure 9.

Figure 11 (sheet 1) is a similar view but showing a ball blank produced by the operation of the cutters shown in Figure 8.

50 In the accompanying drawings the numeral 10 denotes a bed and 11 a bearing bracket of my improved ball-blank forming machine, the latter having a bearing 12 within which a bearing sleeve 13 is secured as by means

of a nut 14 upon the threaded end of the 55 sleeve at one side of the bearing, thereby drawing a shoulder on said sleeve into contact with the opposite side of the bearing, as shown in Figure 2 of the drawings. This sleeve projects for some distance beyond the 60 bearing and an actuating gear 15 is seated against a shoulder thereon and is rigidly secured thereto. A driving sleeve 16 is rotatably mounted in the bearing sleeve 13 and a driving pulley 17 is rotatably mounted 65 on said driving sleeve, said pulley being adapted to receive a belt employed for driving purposes, an annular rib 53 on the pulley extending into an annular recess 54 in a housing 18 mounted upon and secured to 70 the sleeve 13. A transmission gear 19 is mounted upon and secured to the sleeve 16, this gear being approximately of the same size as the gear 15, but preferably having a different number of teeth, in the present 75 instance one less tooth, this for the purpose of obtaining the desired ratio of movement between rotating parts.

Planetary gears 20 are located on diametrically opposite sides of said actuating 80 and transmission gears, said planetary gears being rotatably mounted on bearing studs 21 secured to and projecting from the pulley 17, and each of said planetary gears has a pinion 22 rigidly secured thereto and meshing with a planetary direction pinion 23 that in turn meshes with a driving pinion 24, said direction and driving pinions being rotatably mounted on studs secured to and projecting from the pulley 17, and as shown 85 in Figure 7 of the drawings. The pinion 24 meshes with the transmission gear 19 and thereby, when the pulley 17 is rotated, the driving sleeve 16 will be rotated preferably in a direction the same as that of the 90 pulley. As the pulley rotates faster than said sleeve the latter is rotated in the same direction as the pulley in order to lessen the friction between said rotating parts. All of the gears and pinions above mentioned 95 are located in recesses cut into the housing 100 18, as shown in Figure 7 of the drawings.

A collet 25 extends through the sleeve 13 and has an adjusting nut 26 secured to its outer end, said collet being split at its 105 inner end for contraction purposes. The end of this collet is also slotted to receive feed rollers 27—28, said rollers being peripherally

grooved for the reception of a length of wire 29 and the roller 27 having its periphery formed as a worm on both sides of the groove therein.

5 The wire 29 extends through wire supports 30—31 located in opposite ends of an inner tube 32 which tube extends through the collet and as shown in Figure 2 of the drawings. The wire support 31 has a tapered recess in its inner end to act as a guide for directing the wire thereinto.

The end of the driving sleeve 16 is enlarged to constitute a worm head 33, said head having a chamber within which the 15 feed rolls 27—28 are located, the wall of said chamber being threaded as a worm to mesh with the teeth of the worm formed on the periphery of the roll 27, and the roll 28 being in contact with the roll 27 and being 20 caused to turn by reason of the friction of such contact.

The outer surface of the head 33 is also formed with a worm thread which meshes with the teeth of a worm wheel 34 secured 25 to a shaft 35 rotatably mounted in a bearing block 36 in a cutter head section 37 of a cutter head, said cutter head section also comprising an outer section 38, the section 37 being secured to the side of the pulley 30 17 as by means of screws, and the section 38 being secured to the section 37 as by means of screws, all as shown in Figures 5 and 6 of the drawings. The section 37 is hollow to receive the block 36, and the 35 latter is secured in locked engagement with the section 37 as by means of a locking pin 39 driven tightly in place. Spiral gears 40 are secured to the shaft 35 on opposite sides of the worm wheel 34, as shown in Figures 4 40 and 5 of the drawings, and these spiral gears each mesh with a spiral gear 41 secured to a cutter shaft 42 rotatably mounted in a cutter bearing block 43 adjustably positioned in a recess 44 in the outer cutter head section 45 38, and as shown in Figure 6 of the drawings, there being two sets of cutter mechanisms, and each set being mounted in a block 43. The two blocks 43 are interengaged as by a rib 45 on one block entering 50 a groove 46 in the opposite block, and each of said blocks has a groove 47 to receive cutter supporting blocks 48 secured in said grooves as by means of pins 49. These blocks are located opposite each other 55 in the bearing blocks 43 and their facing edges are each formed to receive a cutter 50, a wire guide 51 and a bearing disc 52 all closely and securely fastened together as a unit. The guides 51 are of larger diameter than the cutters, and they are located 60 on opposite sides of the cutters, as shown in Figure 8, the periphery of each of said guides extending inwardly beyond the periphery of the cutter 50. Sufficient clearance is provided between the peripheral

edges of the guides 51 and discs 52 to prevent the collection of dirt and also permit the necessary adjustment of the cutters. This construction of the cutter units provides an opening through which the wire 70 29 is extended and within which it is retained against any danger of accidental displacement while being acted upon by the cutters, and the construction of the supporting blocks 48 to closely fit this cutter unit 75 guard against any danger of any pieces of metal being lodged in a position where they might be detrimental to the operation of the machine.

The cutters 50 are each formed with a 80 toothed cutting edge, the spaces between the teeth, if desired, being formed approximately on arcs of circles, as shown particularly in Figure 9 of the drawings, as to cutters 55, or the teeth may be of angular form as 85 shown in Figure 8, the former producing blanks 56 as shown in Figure 10 and the latter producing blanks 57 as shown in Figure 11. In either case the crowns of the teeth on the opposed cutters are located 90 sufficiently close to sever the blanks from the wire 29.

The parts travel in the direction indicated by the arrows in the various views so that the mounting of the cutters in the rotatable 95 cutter head section 38 causes the cutters to be rotated or, more precisely speaking, revolved on what may be termed a cutting or forming axis, that is an axis passing between the cutters but in the direction of the diameters thereof, this being the axis of rotation of the cutter head, and the operative connection of the cutter shafts 42 through the medium of the gears 41—40, worm 34 and the worm gear on the outer surface of the 100 head 33 causes the cutters to be rotated in opposite directions upon the axes of the shafts 42, which axes may be termed feeding axes. The wire is passed very slowly between the cutters rotating on their feeding axes while said cutters are rotated comparatively fast on their cutting axes, these cutting axes in fact being the same as the axis of rotation of the device as a whole. In 105 this cutting or forming action none of the metal is removed, but it is displaced or "molded" so that the blanks are of the shape shown in Figures 10 or 11, and such blanks are subsequently subjected to a further operation which causes them to be formed into 110 round shape. From this it will be seen that the cutters in addition to their function of severing the blanks from the wire also form them and in this sense they are formers as well as cutters.

In accordance with the provisions of the patent statutes I have described the principles of operation of my invention, together with the apparatus which I now consider to represent the best embodiment thereof, but I 130

desire to have it understood that the device shown is only illustrative and that the invention may be carried out by other means and applied to uses other than those above 5 set out.

I claim—

1. A forming machine comprising a rotatably mounted support, a head mounted in said support and rotatable independently thereof, a pair of formers to make deep grooves in a wire blank, said formers being mounted in said support to rotate on axes transverse to the axis of rotation of said support, an operative connection between said 10 formers and said head, and means for supporting a wire for delivery to said formers.

2. A forming machine comprising a rotatably mounted support, a head mounted in said support to rotate independently thereof at a different rate of speed, a pair of formers mounted in said support to rotate upon axes transverse to the axis of rotation of said support, an operative connection between said 15 head and formers, and means for supporting a wire for delivery to said formers.

3. A forming machine comprising a rotatably mounted support, a head located within the support to rotate upon the axis independently thereof but at a different rate of speed, a worm thread formed on said head, a pair of formers mounted in said head to rotate upon axes transverse to the axis of rotation of the head, an operative connection between 20 said formers and said worm thread, and means for supporting a wire for delivery to 25 said formers.

4. A forming machine comprising a rotatably mounted support, planetary gears carried by said support, a head mounted in said support to rotate independently thereof and operatively connected with said gears to be rotated thereby, a pair of formers mounted in said support to rotate upon axes transverse to the axis of rotation of said support, an operative connection between said head and said formers for rotation of the latter, and means for supporting a wire for 30 delivery to said formers.

5. A forming machine comprising a rotatably mounted support, planetary gears carried by said support, a head mounted in said support to rotate upon the same axis and independently thereof, an operative connection between said head and said gears to rotate said head at a different rate from that of said support, a pair of formers rotatably mounted in said support, an operative connection between said head and said formers to rotate the latter in said support, and means for supporting a wire for delivery to said formers.

6. A forming machine comprising a rotatably mounted support, a head mounted for rotation in said support, means operated by the rotation of said support for rotating

said head independently of said support at a different speed therefrom, a pair of formers mounted in said support to rotate on axes transverse to the axis of rotation of the support, means for rotating the formers, feed 70 rollers mounted in said head, means for operating said rollers, and means for supporting a wire for delivery to said rollers.

7. A forming machine comprising a rotatably mounted support, a head mounted for 75 rotation in said support, means operated by rotation of said support for rotating said head at a different rate of speed, a pair of formers mounted in said support to rotate on axes transverse to the axis of rotation 80 of the support, means for rotating the formers, feed rollers mounted in said head to rotate on axes transverse to the axis of rotation of said head, means for rotating said feed rollers, and means for supporting wire 85 for delivery to said feed rollers.

8. A forming machine comprising a rotatably mounted support, a pair of formers mounted in said support to rotate on axes transverse to the axis of rotation of said 90 support, a head rotatably mounted in said support and having an internal and an external worm thread, means connected with the external worm thread and with the formers for rotating the latter, feed rolls 95 mounted within the head and in engagement with the internal worm thread for operation of said rolls, and means for supporting a wire for delivery to said rolls.

9. A forming machine comprising a rotatably mounted support, a driving sleeve upon which said support is rotatably mounted, a head carried by said sleeve, means for rotating said support and said sleeve in the same direction but at different rates of speed, a 100 pair of formers mounted in said support to rotate on axes transverse to the axis of rotation of the support, an operative connection between said head and said formers for rotation of the latter, and means for supporting a wire for delivery to said rolls.

10. A forming machine including a collet having a hole to receive a wire extending through said collet, a pair of feed rolls rotatably mounted in said collet, a driving 115 sleeve rotatably surrounding said collet, a support rotatably mounted on said sleeve, means for rotating said sleeve and support at different rates of speed, a pair of formers mounted in said support to rotate on axes 120 transverse to the axis of rotation of said support, and means for rotating said formers.

11. A forming machine comprising a bearing sleeve, a driving sleeve rotatably 125 mounted on said bearing sleeve, a support rotatably mounted on said driving sleeve, means for rotating said driving sleeve and support at different rates of speed, a head carried by said driving sleeve, a pair of 130

formers mounted in said support to rotate on axes transverse to the axis of rotation of said support, means for rotating said formers, and means for supporting a wire for delivery to said formers.

12. A forming machine comprising a bearing sleeve, a gear secured to said sleeve, a driving sleeve rotatably mounted on said bearing sleeve, a gear secured to said driving sleeve, a head carried by said driving sleeve, a support rotatably mounted on said driving sleeve, planetary gears carried by said support and operatively connecting the gears upon said sleeves, a pair of formers mounted to rotate on axes transverse to the axis of rotation of said support, an operative connection between said head and said formers for operating the latter, and means for supporting a wire for delivery to said formers.

13. A forming machine comprising a supporting sleeve, a collet within said sleeve and having an opening for the reception of a wire, a pair of rollers rotatably mounted in said collet, a driving sleeve rotatably mounted on said supporting sleeve, a support rotatably mounted on said driving sleeve, a driving head carried by said driving sleeve, means for rotating said driving sleeve by reason of the rotation of said support, a pair of formers mounted in said support to rotate on axes transverse to the axis of rotation of said support, and means for supporting a wire for delivery to said rollers.

14. A forming machine comprising a rotatably mounted support, a sectional cutter head comprising two sections of substantially the same shape supported one by the other and removably secured to said support, a pair of formers mounted in said head to rotate on axes transverse to the axis of rotation of said head to make deep grooves in a wire blank, means for rotating said formers, and means for supporting a wire for delivery to said formers.

15. A forming machine comprising a rotatably mounted support, an inner cutter head section removably secured to said support, an outer cutter head section removably secured to the inner cutter head section, a pair of formers rotatably mounted in the outer cutter head section to rotate on axes transverse to the axis of rotation of said cutter head sec-

tion, a connection located on said inner section and connected with said formers to rotate them, and means for supporting a wire for delivery to said formers.

16. The process of forming blanks that consists in revolving a pair of formers having peripheral forming teeth on an axis coincident with a plane extending diametrically through said formers to make deep grooves in a wire to produce said blanks and for feeding wire through said formers.

17. The process of forming blanks that consists in simultaneously rotating a pair of formers having peripheral teeth formed to feed the wire between the formers, said rotation being on axes substantially at right angles to the axis of a wire from which the blanks are formed, and also on the axis of said wire to make deep grooves in a wire to produce said blanks.

18. A forming machine comprising a pair of disk shaped formers having peripheral forming teeth located in juxtaposition to produce deep grooves extending around a wire blank for division of the blank into separate articles, means for rotating the formers to produce said grooves, means for revolving said formers on planes coincident with the axis of rotation thereof, and means for supporting a wire for delivery between the edges of said formers and to be fed therethrough by the action thereof.

19. A forming machine comprising a pair of disc shaped formers mounted to revolve upon a forming axis to make deep grooves of like formation in a blank and to rotate upon feeding axes to continuously feed said blank by action in said grooves, and means independent of said blank for rotating said formers to effect said feeding action.

20. A forming machine comprising a pair of disc shaped formers having peripheral forming teeth to make deep grooves of like formation in a blank to produce formations of like shape on opposite sides of said groove, said formers being mounted to rotate upon feeding axes and also upon a forming axis, means for imparting one rate of rotation to said formers upon their feeding axes, and means for imparting another rate of rotation to said formers upon said forming axis.

GEORGE E. ABBOTT.
